HAIR DRIER

Simon Kallmann, Paris, France

Application August 12, 1938, Serial No. 224,427
In France August 28, 1937

1 Claim. (Cl. 34—26)

This invention relates to hair dryers of the type including a blower for circulating air and a heating device for heating the air, and relates particularly to hair dryers of the type commonly used in beauty parlors, by means of which heated air can be applied to the entire back, top and sides of the head.

The hair dryers commonly known at the present time include an air circulating device such as a blower and blast directing means such as, for example, a plurality of perforated tubes or a double wall helmet which is adapted to be applied to the head, and by means of which air is distributed over the scalp. In the helmet or double wall type, the perforations are usually comparatively small, as are the tubes which are present in the first mentioned type. These small perforations restrict the flow of air and tend to build up back pressure which reduces the efficiency of the blower. For this reason, it is necessary either to provide a very powerful blower which causes excessive vibration and noise, or the air must be heated to a higher temperature in order to produce the equivalent drying effect. Either expedient results in discomfort and annoyance to the customer. Another disadvantage of these types of devices is that the drying air is, in fact, not distributed uniformly over the hair. The restricted areas of the numerous small air jets causes the air to dry rapidly at the places of direct contact of the air jets with the hair and much less rapidly at the places between the areas of contact of the blast. As a result, it is necessary to continue the drying operation for a considerable period of time after the hair, at localized points, has already been dried.

An object of this invention therefore is to provide hair dryers which overcome the defects of the dryers described above by distributing the drying air uniformly over the entire scalp, and thus rapidly and uniformly drying the hair.

Another object of the invention is to provide hair dryers which are capable of quickly and uniformly drying the hair at low temperatures and at low initial blast pressures thereby eliminating the discomfort occasioned by high temperature drying and the annoyance caused by the vibration and noise accompanying more powerful blowers.

Other objects of the invention will become apparent from the following description of a typical hair drier embodying the invention.

Hair dryers made in accordance with the present invention include a double wall helmet which is adapted to enclose the top, back and side portions of the head, and which contains a blower

and electric heating resistances for distributing and heating air. The hair drier is characterized by the provision of a movable or rotatable inner wall which is provided with enlarged apertures through which the air is directed and distributed uniformly by rotation of the inner wall. The wall is preferably so arranged that the heated air can at least in part be recirculated by the blower, thus reducing the quantity of heat that is required to heat the air to the desired drying temperature.

More particularly, hair dryers embodying the invention include a housing and an inner wall member, having large apertures therein, which is mounted in front of the blower for rotation during operation of the blower and which is provided with vanes or blades that cause the wall to rotate and distribute the air uniformly. The wall may be spaced at its forward or front edge from the front of the housing to provide a passageway through which air may be delivered rearwardly within the wall toward the blower. The provision of substantially free paths of air flow through the inner wall and between the inner wall and the housing reduces the back pressure to a minimum and thereby allows the blower to operate at maximum efficiency. Hair dryers of this type may be provided with comparatively low powered blowers and small heating elements, and as a consequence are very economical in operation. Nevertheless, the efficiency of the devices is high for the reason that substantially full efficiency of the blower is obtained and heat losses are minimized by at least partial recirculation of the drying air.

For a better understanding of the present invention reference may be had to the accompanying drawing in which:

Figure 1 is a side view of a typical form of a device embodying the invention, shown partly broken away and partly in section to disclose the details of its construction; and

Figure 2 is a view in section taken on line 2—2 of Figure 1.

The form of the invention disclosed in Figures 1 and 2 consists of an outer casing or housing 10 of generally bullet shape, which may be mounted upon a standard 11. The casing 10 is provided with an open end having an inturned flange 12 within which the head or the back portion, top and sides of an individual's head can be received. In the opposite end of the housing 10 is mounted a motor 13 which is supported on a transversely extending member 14 and drives a centrifugal blower or fan 15.

Rotatably mounted within the forward end of

the casing and extending between the outer portion of the casing and the flange 12 is an inner wall member 16 of generally conical shape having open ends, which is rotatably mounted on a spider 17 fixed to the housing 10. Freedom of rotation of the wall member 16 is facilitated by interposing an anti-friction bearing 17' between a flange 18 on the shaft 19 which is connected to the cross member 20 on the wall member 16 and a cap 21 which is threaded onto an annular flange 22 on the spider 17. This construction allows the shaft 19 and the wall section 16 to rotate freely. The wall member 16 may be rotated by means of a plurality of blades or fins 23 which project radially outwardly from the outer surface of the wall member 16. These blades may be straight or curved, as desired, either construction being satisfactory for the reason that the blast of air delivered by the blower 15 travels spirally around the casing.

Adjacent each of the blades 23 is an elongated aperture 24 through which the blast of air is delivered into the interior of the rotatable wall member. The large area of these apertures 24 allows the air to circulate without substantial reduction in pressure, and at the same time distributes the air uniformly over the entire head during rotation of the wall member 16. Air may likewise be delivered into the housing member 16 between the outer end thereof and the flange 12 on the housing member. This construction creates an annular rearwardly flowing column of air which aids in causing recirculation of air through the smaller end of the wall member 16 into the center portion of the blower 15 and again outwardly between the housing 10 and the wall member 16. Some air losses will occur because part of the air will be blown outwardly through the open end of the housing 10. Additional or replenishing air may be drawn into the fan through one or more apertures 25 in the rear portion of the housing 10.

The air may be heated by means of an electric heating coil 26 of the usual type which is preferably disposed between the wall of the housing 10 and the wall portion 16 in the path of the blast of air delivered by the blower 15. Excessive heat losses are avoided for the reason that a large proportion of the air is recirculated through the fan and therefore, after beginning of operation, the

heating device 26 acts to heat the fresh air drawn into the housing 10 and to warm the recirculated air. Likewise, decrease in blast pressure is avoided for the reason that the apertures 24 and the rearwardly directed passage at the front of the device easily accommodate the volume of air that is delivered by the blower and the flow of air is substantially unimpeded.

In order to prevent contact between the rotating wall portion 16 and the hair, it may be desirable to provide some protecting means such as, for example, a grill or cage construction 27 within the wall member 16. The cage construction may suitably consist of a plurality of elliptical wires 28 and transverse annular connecting wires 29 which form a cup shaped cage. The ends of the elliptical wires 28 are connected to the inner surface of the flange 12 of the housing. The cage, therefore, has no projecting elements to catch or disarrange the hair and, also, prevents the hair from coming in contact with inner wall member 16.

While the preferred form of the device has been described above, it will be understood there may be many variations made in the construction such as, for example, in the type of heating devices, blowers, and in the shape of the device and of its component parts without departing from the invention. Therefore, the device described should be considered as illustrative only and not as limiting the scope of the following claim.

I claim:

In a hair drying device, the combination of a housing having an open end, elongated tubular wall member rotatably mounted within and in spaced relationship to said housing, said wall member being perforated to form air passageways, an inwardly directed flange adjacent the open end of said housing overlapping and terminating within said wall member to form a rearwardly opening outlet, a blower for delivering air forwardly between said wall member and said housing and rearwardly through said outlet, and fan blades on the exterior of and for rotating said wall member in response to operation of said blower.

SIMON KALLMANN.
